LOCK

Edward N. Jacobi, Milwaukee, Wis., assignor to
 Briggs & Stratton Corporation, Milwaukee,
 Wis., a corporation of Delaware

Application November 6, 1936, Serial No. 109,417

3 Claims. (Cl. 70—364)

This invention relates to improvements in tumbler locks and refers particularly to pin type tumbler locks in which the rotatable cylinder is secured against rotation by spring pressed 5 tumblers moving from the casing into the cylinder to be lifted to inoperative position by key operable drivers.

In the manufacture of pin type tumbler locks, great pains have been taken to limit the end 10 play of the rotary cylinder to about two thousandths of an inch. If the cylinder is permitted lengthwise motion in excess of this amount, the resulting misalignment between the radial bores in the cylinder and in the casing while the key 15 is in place would prevent the free and unobstructed entrance of the tumbler drivers into the casing bores during withdrawal of the key, as in such instances the ends of the drivers would strike the wall of the casing bore adjacent its 20 tumbler chambers.

In old worn locks, this condition becomes aggravated to an extent that withdrawal of the key necessitates holding the rotary cylinder back in the bore with one hand while the other hand 25 is used to pull the key out.

Ordinary manufacturing processes would produce a variation of about two thousandths of an inch in each of three or four dimensions. This would result in possible misalignment between 30 the radial tumbler chambers of the cylinder and casing of at least six thousandths. Merely to increase the dimensions of the tumbler chambers to allow for such misalignment is not permissible as the accuracy of the lock would then suffer 35 greatly.

Consequently, manufacturers of pin type tumbler locks in the past have resorted to expensive manufacturing operations, such as keeping the casings and cylinders in matched sets 40 after line reaming the tumbler chambers in both parts.

Where the cylinder and casing of the lock are die-cast, the problem becomes particularly grave for if it would be necessary to match and ream 45 these parts in sets, the cost of manufacture would become prohibitive.

With these objections to past and existing pin tumbler locks in mind, it is an object of this invention to provide means whereby the entrance 50 of the tumbler drivers into the casing tumbler chambers is at all times free and unobstructed even though the cylinder is permitted a normal range of lengthwise shifting in the casing bore.

With the above and other objects in view 55 which will appear as the description proceeds,

this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best 10 mode so far devised for the practical application of the principles thereof, and in which:

Figure 1 is a longitudinal sectional view through a pin type tumbler lock embodying this invention;

Figure 2 is a cross sectional view through Figure 1 on the plane of the line 2—2; and

Figure 3 is a plan view of the lock casing per se.

Referring now particularly to the accompanying drawing in which like numerals indicate like 20 parts throughout the several views, the numeral 5 designates the casing of a conventional pin type tumbler lock which may be mounted in a housing or other support 6 and which has a longitudinal bore 7 to receive a rotatable lock cylinder 8. 25

The cylinder 8 is inserted into the bore 7 from its inner end and has an enlarged flange 9 received in a counterbore 10 at the inner end of the casing. Mounted on this flange 9 is an eccentric driving lug 11 through which rotation of 30 the cylinder is imparted to the mechanism controlled.

The cylinder is secured against endwise displacement in the bore by a retaining member 12 embedded in a transverse slot in the casing with 35 its inner edge portion projecting into an annular groove 13 in the adjacent part of the cylinder. In this manner, the cylinder is secured against endwise displacement, but with normal operating clearances and without resorting to special means to restrict the possible end play of the cylinder to a minimum, it may shift endwise as much as 40 six thousandths of an inch.

As is customary in the conventional pin tumbler lock, the cylinder has a plurality of radial bores 45 or tumbler chambers 14 extending from the surface of the cylinder into a longitudinal keyway 15. Slidably disposed in these bores or chambers 14 are tumbler drivers 16 having their inner ends projecting into the keyway to be acted upon by a 50 key 17.

In the locked position of rotation the bores 14 align with radial bores 18 in the casing. Disposed in these radial bores 18 are the pin tumblers 19 urged by springs 20 into the bores 14 as 55

permitted by the drivers 16. The outer ends of the tumbler chambers 18 are closed by a plate 21 extending lengthwise of the casing and secured in place by swedging the metal of the casing over 5 the edges of the plate, as shown in Figure 2.

As pointed out hereinbefore, under normal conditions, there is a possible misalignment between the tumbler chambers 14 and 18 sufficient to cause the ends of the tumbler drivers to engage the 10 shoulders formed by the wall of the bore 7 adjacent the mouths of the tumbler chambers, and this seriously interferes with the withdrawal of the key as the drivers must be free to enter the tumbler chambers 18 during such withdrawal of 15 the key.

In the past, considerable pains were taken to restrict the possible endwise shifting of the cylinder to a minimum in an attempt to prevent such misalignment, but such expedients have proved 20 costly and not entirely satisfactory. The present invention overcomes the difficulty by forming the tumbler chambers 18 with an oval shape, as clearly shown in Figure 3, with the major diameter parallel to the axis of the lock. By this simple 25 expedient, free and unobstructed entrance of the tumbler drivers into the tumbler chambers 18 is assured throughout the full range of possible lengthwise shifting of the cylinder in its bore without in anywise detracting from the accuracy 30 of the lock.

What I claim as my invention is:

1. In a tumbler lock, a bored casing, a rotatable cylinder mounted in the bore, said casing and cylinder having radial bores adapted to be aligned, 35 pin type tumblers and drivers respectively in said radial bores, and the radial bores in the casing being substantially oval with their major dimension lengthwise of the lock so as to assure free entrance of the tumbler drivers into said radial bores in 40 the casing regardless of normal endwise shifting of the cylinder in the casing, while retaining a close fit between the tumbler drivers and said radial bores in the casing to guard against any possible rotation of the cylinder except when 45 the junctures of the tumblers and their drivers are in line with the line of parting between the cylinder and casing bore.

2. In a pin tumbler lock, a bored casing, a cylinder rotatable in the casing bore, means for 50 holding the cylinder against endwise shifting

within normal limits as determined by normal manufacturing practice, said casing and cylinder having radial bores adapted to be aligned, pin tumblers in the radial bores of the casing, key operable drivers in the radial bores of the cylinder projectible into the radial bores of the casing as the key is inserted and withdrawn, and said radial bores in the casing being of oval shape with the major diameter parallel to the axis of the lock to preclude the ends of the drivers striking 10 the edges of the radial bores in the casing upon misalignment of the cylinder and casing radial bores due to normal lengthwise shifting of the cylinder in the casing bore, while retaining a close fit between the tumbler drivers and said radial 15 bores in the casing to guard against any possible rotation of the cylinder except when the junctures of the tumblers and their drivers are in line with the line of parting between the cylinder and casing bore. 20

3. In a pin tumbler lock having a bored casing and a lock cylinder rotatable in the casing bore, the cylinder and casing having radial bores adapted to be aligned in one position of rotation of the cylinder, spring pressed tumblers in the 25 radial bores of the casing, key operable tumbler drivers in the radial bores of the cylinder projectible into the bores of the casing upon insertion and removal of a key, means for holding the cylinder against lengthwise displacement in the bore, 30 said means allowing normal clearance between the parts which entails possible lengthwise shifting of the cylinder in the bore a few thousandths of an inch back and forth which motion is sufficient to objectionably misalign the radial bores 35 in the cylinder and casing, and said radial bores in the casing being oval-shaped with their major diameters parallel to the axis of the lock to compensate for such misalignment and insure unobstructed entrance of the tumbler drivers into 40 the radial bores of the casing during insertion and removal of the key, while retaining a close fit between the tumbler drivers and said radial bores in the casing to guard against any possible rotation of the cylinder except when the junctures of 45 the tumblers and their drivers are in line with the line of parting between the cylinder and casing bore.

EDWARD N. JACOBI. 50
